UNITED STATES PATENT OFFICE.

ERNEST BEARDSLEY SKINNER, OF OGDEN, UTAH TERRITORY.

ELECTRIC BRAKE.

SPECIFICATION forming part of Letters Patent No. 508,851, dated November 14, 1893.

Application filed January 21, 1893. Serial No. 459,248. (No model.)

To all whom it may concern:

Be it known that I, ERNEST BEARDSLEY SKINNER, a citizen of the United States, residing at Ogden city, in the county of Weber and the Territory of Utah, have invented a new and useful Electric Brake, of which the following is a specification.

My invention relates to improvements in electric brakes and consists in the novel construction thereof, and the objects of my improvements are: first, to provide the facilities to obviate the necessity of utilizing the electric current to hold the brake rigidly in place after setting; second, to increase the power and efficiency of the electric coils by providing a complete magnetic circuit; third, to provide an electric brake that may be connected, and operate in conjunction with the ordinary hand-brake, without interfering with the hand brake, both being applied and adapted to operate the same set of shoes. I attain these objects by the mechanism illustrated in the accompanying drawings, which are referred to and are made a part of this specification, and in which—

Figure 1 is a longitudinal section of the brake, embodying my improvements. Fig. 2. is a plan view, showing the method of connecting the brake to the rods; and Fig. 3. is a diagram of the wire connections.

Similar letters and figures refer to similar parts throughout the several views.

In Fig. 1 of the accompanying drawings, C. represents a solenoid, or coil of wire wound on a brass or copper tube, M., and insulated electrically therefrom, and inclosed by the iron tube, t. The iron head, F., forms a support for one end of the tubes, M. and t, and also a guide for the iron plunger, B. F'. supports the other ends of the tubes, M. and t. and also the coil j.

B. is a plunger, made of iron, with a slot, N., cut in the end.

A. is the end of the lever, connecting with the brake rods, and is free to move forward and back in the slot, N.

L. is a lever, working on a fulcrum I., against the shoe, S.

S. is a shoe, made of wood, or other suitable material, which is pressed against the plun-

ger B., by the lever, L., and the spring, R., thus forming a clutch on the plunger, B., and normally holding plunger B., rigidly in place.

D. is a spring which acts against the plunger, B.

j. is a coil of wire or solenoid, having iron heads, u, and inclosed by an iron tube, O, the same as coil, C., and is termed the release coil, as its function is to release the brake.

P. is an iron plunger for coil, j, and is connected to the lever, L.

R. is the clutch spring, coiled around the plunger, P., and acts normally against the plunger, B., through the agency of the lever, L., fulcrum, I., and shoe, S.

E. indicates the timber in the car frame, which supports the brake.

G. is a passage, leading into the end of the tube, M., through the iron head, F'.

H. is a check valve, so constructed that it will let the air in tube, M., pass freely out, and can control the amount let in.

t. and O. are iron tubes, inclosing coils, C. and j. and provide magnetic paths for the lines of magnetic force to return, after passing through plungers, B. and P. and coil C. and j.

Fig. 2 is a plan view of the trucks of a railway car, showing the methods of connecting the brake, by means of levers connecting with the brake shoes, which may be so arranged as to be pressed against the wheels or the rail.

W and B. (Fig. 2,) indicate the brake and the plunger connected to the lever, A., which connects with the brake rods.

Fig. 3 is a diagram, showing the arrangement of the wire connections to the coils, C. and j., in which y. represents the dynamo, or source of electricity; C. and j. the electric coils; 1, the wire leading from the source of electricity to the switches, 5 and 6, both of which connect with wire 1; 2, the wire leading from switch 5 to coil j., in which plunger, P. operates; 3, the wire leading from switch 6, to coil C., in which plunger B., operates, and wire 4, forms a return circuit for both coils.

In the application of the brake to the single trolley system on electric cars, wire 1 may connect with the trolley, and wire 4 forms a

100

return circuit for both coils. Both switches, 5 and 6, may be so constructed as to be controlled by one lever, or there may be a separate lever for each switch.

5 The action of the brake is as follows: When the electric current is not applied to either coil, C. and j., the spring, R. presses against the end of the lever, L., thus forcing the shoe, S. firmly against the plunger, B., holding plunger, B., rigidly in whatever position it should happen to be. The length of the lever, L., and the tension of the spring, R., are so regulated as to make the work of holding the plunger B., firmly in place, when the 15 electric current is shut off from coil j. positive and effective. If a current of electricity be passed through the coil, j., the iron plunger, P. will be drawn up into the coil, j., against the tension of the spring, R., and the weight 20 of the plunger, P., according to the well known law of the attraction of a solenoid for an iron bar, when the solenoid is excited by a current of electricity. This movement of the plunger, P., acting upon the lever, L. causes the shoe, 25 S., to drop away from the plunger, B., thus leaving plunger, B., free to move into or out of the tube, M. Then, if a current of electricity is sent through the coil, C., the plunger, B., will be drawn into the tube, M. (the 30 same principle being applied as that already referred to in regard to plunger, P., and coil, j.) carrying with it the end of the brake lever, A., with a strength limited only by the amount of the current sent through the coil, C., thus 35 setting the brake.

To set the brake, the electric current is first sent through the release coil, j., by a suitable switch, for the purpose of allowing the plunger, B., to act freely by releasing it from the 40 pressure of the shoe, S. Then the current is applied to the coil, C., setting the brake as indicated, the plunger B., moving forward into the tube, M., in response to the action of the electric current, and carrying with it the 45 brake rods which connect with the shoes, applied to the wheels or rails. Then the electric current is stopped from passing through the release coil, j., when the plunger B., will be held rigidly in position by means of the 50 spring, R. and shoe, S. Then the current may be stopped from passing through the brake coil, C., and the pressure of the shoe, S., against the plunger B., will hold the brake set. To release the brake, the current is 55 passed through the release coil, thereby relieving plunger, B., from the pressure of the shoe, S., which will be pushed out by the spring, D., thereby acting upon the brake rods, and causing the shoes to drop away 60 from the wheels. It will be seen that to set the brake, the electric current need only be used momentarily, or long enough to apply the shoe, S., to the plunger, B., by means of the plunger, P. This, I claim is a great economy, insomuch as there is not now in exist- 65

ence any electric brake, to my knowledge, that does not require the application of the electric current continuously, while the brake is set. The iron heads, F. and F', and the tubes t. and O., are provided to form a complete magnetic circuit, composed of iron. Actual experiment has shown that the combination in an electric brake of the complete magnetic circuit referred to, materially increases the power and efficiency of the coils. 75

I am aware that solenoids, with complete magnetic circuits, have been used in combination with electric drills, advantageously, but I believe the application of complete magnetic circuits, composed of iron, for the 80 purpose indicated, by means of the iron heads, F. and F', and the tubes, t. and O., is a novel combination in electric brakes, that is new with me. To guard against sudden action or jar when the brake is released by means 85 of the coil, j., acting upon shoe, S., the air valve, H., is provided. Plunger B., fits air tight in the tube, M., by being provided with a suitable packing ring, k. As the brake is set, the plunger moves forward into the tube, M., and 90 the air in the tube, M., will be forced out through the passage, G., and valve, H. When the plunger, B., is released, it will be held back against the action of the spring, D. sufficiently to prevent jar by the partial vacuum 95 formed, as the plunger B., is pushed out. The vacuum is controlled by the valve, H., by allowing more or less air to re-enter. 100

The electric brake switches used may be so constructed as to be controlled by one lever, or there may be a separate switch for each coil. The spring, R., lever, L. and fulcrum I., adapted to press the shoe, S., against plunger, B., may be used to hold the brake rigidly in position after setting, in connection 105 with any electric brake, without departing from my invention. The hand brakes may be connected with lever, A., also, and in case the hand brakes are used, the end of lever, A., will slide in the slot, N., thus not 110 interfering with the electric brake.

Having described my invention, what I claim, and desire to secure by Letters Patent, is—

1. The within described electric brake, composed of solenoids, or wire coils C. and j., in which the plungers, P. and B. move forward or back, in response to the action of the electric current, and the springs, D. and R., and having metallic heads, F. and F', and tubes, t. and O. to form a complete magnetic circuit; and having passage G., check valve, H., springs D. and R., and lever, L., acting upon fulcrum, I., against shoe, S., all substantially as set forth for the purpose specified. 115
  2. In an electric brake, the combination of the solenoid j., having iron heads, u., and tube, O., in which plunger, P., moves forward and back in response to the action of the electric current, and the spring, R., with the spring 120
- 125
- 130

R., lever L., fulcrum, I., and shoe, S., adapted to release the brake, after setting, all substantially as specified, and for the purpose stated.

3. With an electric brake the combination of a friction block, or shoe S, acting against a plunger B, through the agency of a spring R, lever L, and fulcrum I, for the purpose of holding the plunger B, firmly in place after

the brake is set and without any assistance from the electric current, all substantially as to and for the purpose stated.

ERNEST BEARDSLEY SKINNER.
